Primary Examiner — Mimosa De(74) *Attorney, Agent, or Firm* — Nixon Peabody LLP; Thomas P. Pavelko(57) **CLAIM**

The ornamental design of a frame for sectional chair, as shown and described.

DESCRIPTION

FIG. 1 is a perspective view of the frame for sectional chair.

FIG. 2 is a front view of the frame for sectional chair.

FIG. 3 is a rear view of the frame for sectional chair of FIG. 2.

FIG. 4 is a left side view of the frame for sectional chair of FIG. 2.

FIG. 5 is a right side view of the frame for sectional chair of FIG. 2.

FIG. 6 is a top view of the frame for sectional chair of FIG. 2.

FIG. 7 is a bottom view of the frame for sectional chair of FIG. 2; and,

FIG. 8 is a perspective view of one exemplary environment of use, where a seat (shown in dotted lines forming no part of the claimed design) is coupled to the upper portion of the frame for sectional chair.

The ornamental design as shown in the accompanying figures of drawings apply to the frame for sectional chair, but any element illustrated by dotted lines is not included within the ornamental design.
